UNITED STATES PATENT OFFICE.

LEROY H. NAZER AND JAMES L. JENSEN, OF COWLEY, WYOMING.

ENDLESS SICKLE.

1,257,101.

Specification of Letters Patent. Patented Feb. 19, 1918.

Application filed October 30, 1916. Serial No. 128,519.

To all whom it may concern:

Be it known that we, LEROY H. NAZER and JAMES L. JENSEN, citizens of the United States, both residing at Cowley, in the 5 county of Big Horn and State of Wyoming, have invented certain new and useful Improvements in Endless Sickles, of which the following is a specification.

This invention relates to cutting mechanisms for use in connection with agricultural machines.

The object of the present invention is to provide a cutting mechanism which may be readily attached to any agricultural machine, the said cutting mechanism being in the form of an endless belt, thereby doing away with the vibration and noise usually found in the reciprocating type cutter.

With this and other objects in view the 20 invention consists of a cutter, a chain operating within said bar and carrying knives, sprockets engaging said chain, and means for imparting motion to the said sprockets.

In the drawing:—

25 Figure 1 is a plan view of an endless cutting mechanism constructed in accordance with the present invention;

Fig. 2 is an elevation of the same.

Fig. 3 is an enlarged transverse section 30 looking through the cutter bar and showing the endless cutting knives in position.

Fig. 4 is an enlarged view of one end of the cutter bar with the guard and knives removed.

35 Fig. 5 is a detailed view of the means for driving the sprockets.

Fig. 6 is a detailed view illustrating the manner of engagement of the sprockets with the links of the endless chain.

40 Fig. 7 is an enlarged detailed plan view of one end of the cutter bar, showing the device for separating the hay.

Fig. 8 is an enlarged detailed elevation of one of the sprockets.

45 Fig. 9 is an enlarged plan view of a portion of the chain and knives, the upper flight of the chain being shown in full lines and the lower flight in dotted lines.

Referring to the drawings the improved 50 cutting mechanism comprises an inclosed casing open upon its front face and provided with enlarged end portions which are closed, and as arranged in the form shown in Fig. 2 and is provided with the end portions 4 and 5. Said casing is formed with a longitudinal slot 6 in which the endless chain

which carries the cutting knives is adapted to move. The chain which is designated as at 7 is composed of a number of links 8 each of the said links being provided with a slot 9 in one end, and an engaging lug 10 at its opposite end. Attached to these links by means of bolts or rivets 11 are angularly shaped knives 12, these knives being provided with diagonal cutting edges 13. The chain 7 is in an endless form, and is adapted to travel back and forth within the slot 6, the upper and lower flights of this chain being separated by a thin strip 14.

The casing 1 is provided along its lower 70 edge with a series of slots 15 to receive lugs 16 formed on the guard 18. The rear end of this guard 18 is secured to the cutter bar 1 through the medium of the bolt 19.

The chain 7 is driven by means of 75 sprockets 20, one of these sprockets being provided in each of the portions 4 and 5, the teeth 21 of which engage slots 22 formed in each of the links 8. One of the sprockets 20 has secured upon its rear face a pinion 24 80 engaged by the pinion 25^a and carried by the shaft 25, the bearings 26 of the shaft 25 being supported upon a portion 27 of the machine. Upon the opposite end of the shaft 25 is a beveled pinion 28 driven by a 85 gear 29 receiving its power from a suitable source. A shield 30 is provided for the sprocket and gear 28 and 29. If desired a suitable casing may inclose the shaft 25 as shown.

90 The front portions 4 and 5 of the casing which inclose the sprocket 20 are provided each with a cover 31 as shown.

The casing 1 may have secured to its end as shown a device for separating the standing hay, in order to let the end of the cutting mechanism pass. This device consists of a member 32 having one end secured to the casing, its opposite end being supported by a brace 33. The usual mole shoe 34 is shown 100 as carried by the casing.

From the foregoing description when taken in connection with the accompanying drawings, it will be seen that the invention provides a simple and efficient cutting mechanism, for agricultural machines, which will 105 eliminate the unnecessary jar and noise.

What is claimed is:—

In combination with an inclosed integral casing with enlarged end portions, the front 110 face of the casing having a recess extending intermediate said enlarged ends, sprocket

wheels mounted within said enlarged end portions, and an endless chain passing about said sprocket wheels and having cutter knives mounted thereon, forwardly extending grain separating fingers projecting from the outer of said enlarged end portions and secured together near their ends which intersect, and a shoe secured to the under surface of the end portion having said fingers, 10 and its forward end upwardly inclined and positioned intermediate and below the fingers.

Signed at Cowley in the county of Big Horn and State of Wyoming this 25 day of September A. D. 1916.

LEROY H. NAZER.
JAMES L. JENSEN.
